UNITED STATES PATENT OFFICE

100,611

DESIGN FOR A CANDLE

Norbert J. Baumer, Baltimore, Md.

Application June 17, 1936, Serial No. 63,341

Term of patent 14 years

To all whom it may concern:

Be it known that I, Norbert J. Baumer, a citizen of the United States, residing at Baltimore, State of Maryland, have invented a new, original, and ornamental Design for Candles, of which the following is a specification, reference being had to the accompanying drawing, forming a part thereof, and in which:

Fig. 1 is a side view of a candle showing my new design,

Fig. 2 is a top plan view,
Fig. 3 is a cross-sectional view on the line
3—3 of Fig. 1, and
Fig. 4 is a bottom plan view.
What is claimed is:
The ornamental design for a candle, as shown.
In testimony whereof, I hereunto affix my signature.

NORBERT J. BAUMER.
